UNITED STATES PATENT OFFICE.

EDWARD F. CRANE, OF HOBOKEN, NEW JERSEY, ASSIGNOR OF ONE-HALF TO ARTHUR J. GEYMES, OF EAST ORANGE, NEW JERSEY.

APPLIANCE FOR VESSELS.

1,169,128.

Specification of Letters Patent. Patented Jan. 25, 1916.

Application filed May 24, 1915. Serial No. 29,977.

To all whom it may concern:

Be it known that I, EDWARD F. CRANE, a citizen of the United States, residing at the city of Hoboken, in the county of Hudson and State of New Jersey, have invented certain new and useful Improvements in Appliances for Vessels, of which the following is a specification.

I will first describe my improvements in detail and then point out the novel features in the claims.

In the accompanying drawings Figure 1 is a side view of a vessel provided with my improvements; Fig. 2 is a side view showing the vessel illustrated in Fig. 1 submerged and with buoys attached to said vessel shown as floating on the surface of the water; Fig. 3 is a partial sectional view taken through the vessel and one of the containers with which the vessel is provided; Fig. 4 is a plan view of a container; Fig. 5 is a sectional view taken through the plane of the dotted line 5—5, Fig. 4; Fig. 6 is a sectional view taken through the plane of the dotted line 6—6, Fig. 4; Fig. 7 is a partial outside view of a container, and Fig. 8 is a sectional view through the plane of the dotted line 8—8, Fig. 6, looking in the direction indicated by the arrows in Fig. 6.

Similar letters of reference designate corresponding parts in all the figures.

A designates the hull of a vessel shown as provided with containers, B. Each container B is shown as provided with a buoy, C, which forms a head or cover for its container B, and the buoy C has a hollow body and a closed top provided with a spider or crown, D, on which electric light bulbs, E, are shown as arranged. These electric light bulbs E are shown as connected with a battery, E', by means of wires, e e'; which wires are shown as in connection with contact pieces, e². The battery E', wires e e' and contact pieces e² are shown as arranged within the body of the buoy C.

Rods, as F, are shown as mounted on the outer ends of rock shafts f journaled at opposite sides of the buoy C. A signaling device, such as a flag, f', may be provided at one end of each rod F and the other end with a weight, as f². Each shaft carries at its inner end an electric switch, e³, which switch, as shown in Fig. 8, is intended to be out of contact with the contact pieces

e² when the buoy C is resting properly on its container B. When the buoy C is in position on its container B the weighted ends of the rods F normally rest on pins, b², shown as arranged on the sides of the container.

G designates tubing, one end of which is shown as standing within and protected by the spider D, whence it is led down through the buoy C, within the container B and through its bottom, thence through an opening g in the hull, and through suitable packing g' therein, which will prevent the entrance of water to the vessel but will permit the tubing to slip through. Thence the tubing leads down within the vessel and its length is stored therein, as by being coiled within a receiver g² as best seen in Fig. 3. At or near the end of the tubing G which is attached to the buoy C, suitable means, 75 such for instance as a valve, may, if desired, be employed to prevent the ingress of water into the tubing G.

G' designates an air pump in the vessel A through which air may, if desired, be drawn into the vessel.

In the drawings I have shown a telephone cable H wound around the tubing G, but if preferred the telephone cable might be arranged within the tubing G or otherwise attached to the buoy C. A suitable telephone instrument, H', is located in the vessel A and connected with the cable H. A rope, I, is shown as attached at one end to the bottom of the buoy C and at its other end to a suitable cable or chain, I'. One end of the cable or chain I' passes through a suitable opening, a, in the hull A and is shown as attached to a cap, I², to which cap braces, I³, are shown as securely fastened. These braces I³ are also shown as fastened to the hull itself.

A proper packing, a', may, of course, be provided to prevent the entrance of water to the vessel through the opening a.

J J designate rods shown as held in place on the sides of the container B by suitable guides, b'. The upper ends of these rods J J are shown as bent or hooked at j j, while the lower ends of the rods J J are shown as passing into the hull and as provided with hand wheels, j'. Suitable packing may, of course, be employed as at j² to prevent the flow of water into the vessel.

A buoy C being placed in position as a

head or cover for its container B the rods J J may be so turned that the hooks or bent portions j j thereof will fit over on the buoy and hold the buoy securely in place, and a rubber gasket k may, if desired, be used to insure a close joint between the buoy C and its container and keep the contents of the latter dry.

Should the vessel become submerged the hand wheels j' j' may be turned, thereby so turning the rods J J as to remove the hooked portions j j thereof from over the buoy C and thus enable the buoy C to rise. As the buoy C rises it carries up with it the rods F and the weighted ends of the rods F will cease to rest on the pins b². The weight f' will cause the end of the rod F to which it is attached to drop and the end of the rod F to which the flag f' is attached to rise, as indicated in dotted lines in Fig. 7. At the same time the electric switch e² attached to the rock shaft f will be brought into contact with the contact pieces e², thereby closing the electric circuit and lighting up the bulbs E. As the buoy C rises it of course carries up with it the tubing G, which slides through the packed opening g' and uncoils its length from within the receiver g², and it also carries up with it the comparatively light rope I, which uncoils from the container B. The latter will be of sufficient size to hold a good sized coil of the cable or chain I' as well as a good sized coil of the rope I, and the rope should be light enough to permit the rise of the buoy but strong enough to be used for raising the cable or chain.

When the buoys C reach the surface of the water they float thereon as shown in Fig. 2 and display signals such as the flag and the electric lights.

By means of the air pump G' air may be drawn into the vessel through the tubing G connected to one of the buoys C and air may be carried from the vessel through the tubing G connected with the other buoy C.

When a rescuing vessel reaches the buoy C the buoy C may be drawn on board such rescuing vessel and a telephone instrument properly attached to the cable H so as to permit communication with the interior of the submerged vessel. The cables or chains I' may be drawn up by means of the ropes I, and when the cables or chains I' are reached the submerged vessel may be thereby drawn to the surface.

It will, of course, be readily understood that instead of placing the containers B on the outside of the vessel such containers might be countersunk within the hull, leaving the buoy C exposed.

By my improvements I provide means by which the location of a submerged vessel may be readily determined and by which a submerged vessel may be readily brought to the surface. At the same time there is pro-

vided means for establishing communication with a submerged vessel and means by which a supply of fresh air may be introduced to a submerged vessel and foul air carried therefrom.

What I claim as my invention and desire to secure by Letters Patent is:

1. The combination with a vessel, a container mounted on its hull, the bottom of the container and the hull having registering openings with packing therein, a cable having its lower end secured in the hull and its body passing through one of said openings and stored within the container, and a tubing stored within the hull and its body passing through the other of said openings; of a buoy normally closing the upper end of the container, the upper end of the cable being attached to said buoy and the upper end of the tubing passing through said buoy, and means within the vessel for releasing the buoy from the container.

2. The combination with a vessel, a container mounted thereon, the bottom of the container and the hull of the vessel having registering openings, a heavy cable whose lower end is fast within the hull and whose body passes through said openings and is stored within the container, and a light rope secured to the upper end of the cable and also stored within the container; of a buoy mounted above said ropes and having its top overlying the upper end of said container and packed for making a close joint therewith, and means operable from within the vessel for maintaining the buoy in position or releasing it.

3. The combination with a container carried by the hull of a vessel, and a stop on the wall of the container; of a buoy mounted on the container, a flexible line connecting them, a rod pivotally mounted on the buoy and having one end weighted and resting on said stop when the buoy is in place, and a signal at the other end of the rod raised by the descent of said weighted end as the buoy rises.

4. The combination with a container carried by the hull of a vessel, and a stop on the wall of the container; of a buoy mounted on the container, a flexible line connecting them, a rock shaft journaled in the buoy, a rod secured across one end of the shaft and having a weight resting on said stop when the buoy is in place, the body of said buoy being hollow, electric lights carried upon such buoy, a generator therefor mounted within the hollow body, a circuit connecting it with the lights, contacts arranged within said circuit, and a switch at the inner end of said rock shaft adapted to close the circuit between such contacts when said weight falls.

5. The combination with a support mounted on the hull of a vessel, a pin on said support, and a hollow floating element mounted

on the support and carrying a spider; of a rock shaft journaled in said element, a rod fast across its outer end and having a signal at one extremity and a weight at the other extremity resting on said pin to depress said flag when the element is in position on the support, an electric signal on said spider, a generator for such signal located within the

element, and switching means for closing the circuit from the generator to the signal, 10 said means being carried by the inner end of the rock shaft.

EDWARD F. CRANE.
